DESIGN FOR A HOLDER FOR CONDIMENTS SHAKERS OR THE LIKE

D. Bryce Woodruff, Sonora, Calif.

Application December 2, 1941, Serial No. 104,441

Term of patent 7 years

To all whom it may concern:

Be it known that I, D. Bryce Woodruff, a citizen of the United States, residing at Sonora, in the county of Tuolumne and State of California, have invented a new, original, and ornamental Design for a Holder for Condiment Shakers or the like, of which the following is a specification, reference being had to the accompanying drawing, forming part thereof.

for condiment shakers or the like, showing my new design;

I claim:

The ornamental design for a holder for condiment shakers or the like, as shown.

D. BRYCE WOODRUFF,
